Primary Examiner — John M Otte(74) *Attorney, Agent, or Firm* — Brian J. Colandreo;
Jeffery T. Placker; Holland & Knight LLP(57) **CLAIM**

The ornamental design for a display screen or portion thereof with a graphical user interface, as shown and described.

DESCRIPTION

The FIGURE is a front view of a display screen or portion thereof with a graphical user interface showing the claimed design.

The broken lines are included for the purpose of illustrating portions of the display screen or portion thereof with a graphical user interface that form no part of the claimed design.
